[57] **ABSTRACT**

An elastic-type exercising device to be attached to the feet of a user. The exercising device has two feet-engaging members attached to the respective ends of a single elongated piece of resilient material. Two of the devices are to be positioned parallel to each other so that users may place feet in two adjacent foot-receiving members and exercise against the resistance of the other user when his feet are in adjacent foot-engaging members.

RESILIENT-TYPE LEG-EXERCISING DEVICE

This invention relates to new and useful improvements in exercising devices, particularly exercising devices which may be in the form of a competitive game or the like.

The principal object and essence of the invention is to provide an exercising device which is particularly suited for use in the exercising of the legs.

Another object of the invention is to provide a device of the character herewithin described in which the resiliency of strips or ropes of rubber or the like is utilized, it being understood that the greater the extension of the ropes or strips, the greater the resistance thereof thus giving an exercising device which is variable in the force required to operate same.

A yet further object of the invention is to provide a device of the character herewithin described which is simple in construction, economical in manufacture, and otherwise well suited to the purpose for which it is designed.

With the foregoing in view, and such other or further purposes, advantages or novel features as may become apparent from consideration of this disclosure and specification, the present invention consists of, and is hereby claimed to reside in, the inventive concept which is comprised, embodied, embraces or includes in the method, process, construction, composition, arrangement or combination of parts, or new use of any of the foregoing, of which concept, one or more specific embodiments of same are herein exemplified as illustrative only of such concept, reference being had to the accompanying Figures in which:

FIG. 1 is a top plan view of one of the exercising devices.

FIG. 2 is a side elevation of FIG. 1.

FIG. 3 is a side elevation of an alternative embodiment with one end fixed to a supporting surface.

FIG. 4 is an enlarged fragmentary view showing the engagement of the foot with the safety loop and the toe engaging portion.

In the drawings like characters of reference indicate corresponding parts in the different figures.

Proceeding therefor to describe the invention in detail, the device consists of a rope or strip 10 made of resilient material such as rubber. It can be a plurality of single strands encased within a woven casing or, alternatively, it can be a solid strip. Dealing first with the embodiment shown in FIGS. 1 and 2, a foot-engaging attachment collectively designated 11 is secured to each end of the strip 10 by conventional means such as sewing or stapling (not illustrated). The foot-engaging attachments include a substantially rectangular pad 12 upon which the foot of the wearer rests, and a toe-engaging pocket or cap 13 extending upwardly and over the front end 14 of the sole plate or pad 12, it being understood that the pockets 13 are provided with closed ends 15 into which the toe engages.

Secured to the ends 16 of the strips or ropes 10 adjacent the attachments 11, is a safety loop 17. This loop is also resilient, but is adapted to extend around the ankle or instep area 18 of the user fairly snugly.

The device is adapted to be used in pairs and by two people. The devices are laid side by side on the floor with the ropes 10 extended but not stretched. Each user engages his left and right foot in adjacent attachments 11 so that they are standing back to back.

Exercise is obtained by each of the users attempting to walk away from the other against the resiliency or elasticity of the ropes or strips 10.

It will, of course, be appreciated that the farther apart the users become, the greater the strain so that there comes a point where neither user can take a further step under which circumstances the greatest exercising strain is reached, such strain at this point, of course, being isometric.

The safety loops 17 prevent inadvertent displacement of one of the attachments from the foot of the user with the subsequent danger of it snapping back and striking the other user.

FIG. 4 shows the method of attachment of the foot of the user into the attaching portion 11 with the safety strap or loop 17 in position and the toe 18 engaged within the pocket 13.

FIG. 3 shows a modification in which the foot-attaching portions 11 are provided on one end 19 of the strap or rope 10.

The other end 20 is provided with a ring 21 or the like which may be attached to a bracket 22 secured to a vertical supporting surface 23 such as a wall. Here again two devices are used, one for each foot, the user walking away from the wall in the direction of arrow 24 until he can move no further.

When used with two people, it will of course be appreciated that a competitive effort is involved and that if continued strain is used, one person may actually force the other to give way and move rearwardly.

Various modifications can be made within the scope of the invention concept which is herein disclosed and/or claimed.

What I claim as the present invention is:

1. Exercising apparatus for use by two persons standing back to back consisting of two identical devices positioned side by side on a supporting surface, each of said devices comprising an elongated resiliently stretchable element and a pair of foot-receiving members secured to the opposite ends of said element, each of said foot-receiving members including a toe cap and the toe caps of the two foot-receiving members of each device being oriented outwardly in opposite directions, so that when the two devices are positioned side by side on a supporting surface as aforesaid, the elongated stretchable elements of the two devices are substantially parallel and feet of two participants are received in the foot-receiving members at the respective opposite ends of the two devices.

2. The apparatus as defined in claim 1 wherein each of said foot-receiving members also includes a sole plate secured to said elongated element of the associated device, said toe cap being provided on said sole plate.

3. The apparatus as defined in claim 1 wherein each of said foot-receiving members also includes an ankle engaging loop connected to said elongated element of the associated device.
